CLAIM

The ornamental design for a decorative hair strip, and shown and described.

DESCRIPTION

FIG. 1 is a perspective view of a design for a decorative hair strip attached to a helmet;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The helmet is shown in broken lines for illustrative purposes only and forms no part of the claimed design.
